US00D971745S

(12) **United States Design Patent** (10) **Patent No.:** **US D971,745 S**
(45) **Date of Patent:** **** Dec. 6, 2022**

(54) **DISPENSER**

(71) Applicant: **Lucas Packaging Group, Inc.**, Sussex, NJ (US)
(72) Inventor: **Frank Francavilla**, Sussex, NJ (US)
(73) Assignee: **Lucas Packaging Group, Inc.**, Sussex, NJ (US)

(**) Term: **15 Years**

(21) Appl. No.: **29/772,351**

(22) Filed: **Mar. 1, 2021**

(51) **LOC (13) Cl.** **09-01**

(52) **U.S. Cl.** **D9/727**
USPC **D9/727**

(57) **CLAIM**

The ornamental design for a dispenser, as shown and described.

DESCRIPTION

FIG. 1 is a top perspective view of a dispenser, showing my new design.

FIG. 2 is a bottom perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof;

FIG. 8 is a bottom plan view thereof; and,

FIG. 9 is an exploded front perspective view thereof.

The broken lines in the drawings depict portions of the dispenser that form no part of the claimed design.

1 Claim, 9 Drawing Sheets
